UNITED STATES PATENT OFFICE.

JAMES M. REDDY, OF CHICAGO, ILLINOIS.

DESIGN FOR AN OIL-STOVE.

SPECIFICATION forming part of Design No. 12,578, dated November 22, 1881.

Application filed September 27, 1881. Term of patent 7 years.

To all whom it may concern:

Be it known that I, JAMES M. REDDY, a citizen of the United States, residing at the city of Chicago, in the State of Illinois, have invented and produced a new and original Design for Oil-Stoves, of which the following is the specification, reference being had to the accompanying drawings, and to the figures and letters thereon.

10 Figure 1 is an upright front view of my newly-designed oil-stove. Fig. 2 is a top view of the same. These two views are necessary to fully illustrate my design.

In Fig. 1 is shown the design, in the main composed of the segmental arches *aaa*, through which are the doors *SSS*, and through these doors are the mica windows *ddd*, which lead into the presence of the flame, and the gothic arches *b b*, located between the segmental arches *aaa*. The surface *cc* beneath the gothic arches *b b* may be a highly-polished surface, such as nickel, silver, or brass. Below these two systems of arches is another series of segmental arches, *eee*, smaller than the first. These latter arches are always open, and lead into the space below the domes of the burners and above the oil-pot, and through which passes air to the flame; also, through these latter arches pass the ends of the ratchet-shafts *ii*, which raise and lower the wicks. At each end of the stove, and in line with the smaller arches *eee*, is lattice-work

35 *RR*. Above the segmental and gothic arches is the protruding rim *o*, extending around the upper edge of the stove, and above this rim are the pinnacles *ll*, also extending around the upper edge of the stove.

In Fig. 2 it will be seen that the stove is in the form of a parallelogram with circular ends, having three heating-holes, *xxx*, and at the rear is the oil-pot *T*.

40

I claim—

1. The design for an oil-stove herein shown and described, the same consisting, in the main, of the segmental arches *aaa* and gothic arches *b b*, arranged as shown.

45

2. The design for an oil-stove herein shown and described, the same consisting of the segmental arches *aaa*, gothic arches *b b*, the segmental arches having the doors *SSS*.

50

3. The design for an oil-stove herein shown and described, the same consisting of the segmental arches *aaa*, gothic arches *b b* below them, the series of smaller segmental arches *eee*, and the lattice-work *RR* at each end of the stove, substantially as shown and described.
